UNITED STATES PATENT OFFICE

JOHN LEWIS PRESTON, OF WICHITA FALLS, TEXAS

FRACTURE SPLINT

Application filed April 3, 1929. Serial No. 352,264.

The present invention relates to improvements in splints and has reference more particularly to a splint for treating mandibular fractures.

5 One of the important objects of the present invention is to provide a fracture splint wherein the same includes complementary trays to receive the upper and lower jaws, said trays being of channel-shaped formation to properly confine the cement or modelling compound therein, additional means being associated with the trays for securing the same together in proper relation when in position within the patient's mouth.

10 15 A still further object is to provide a fracture splint of the above-mentioned character wherein the uppermost tray is formed with a depending lug at the front portion thereof, said lug providing a means for spacing the trays apart, and further providing a means whereby a detachable handle may be associated therewith for facilitating the insertion or removal of the upper tray.

20 25 A further and important object is to provide a fracture splint of the above-mentioned character wherein coacting means is arranged at the inner or rear portions of the trays to prevent lateral movement of the trays with respect to each other when positioned in the patient's mouth.

30 A still further object is to provide a fracture splint of the above-mentioned character that will at all times be positive and efficient in carrying out the purposes for which it is desired, the same being further simple in construction, inexpensive, strong and durable.

35 Other objects and advantages of the invention will become apparent from the following description when taken in connection with the accompanying drawings.

In the accompanying drawings wherein like reference characters indicate corresponding parts throughout the same;

40 45 Figure 1 is a side elevation of the fracture splint embodying my invention showing the complementary trays positioned in the mouth of the patient and illustrating the manner in which said trays are secured together.

50 Figure 2 is a longitudinal vertical sectional view therethrough.

Figure 3 is a front elevation of the complementary trays secured together.

Figure 4 is a vertical sectional view taken approximately on the line 4—4 of Figure 1.

Figure 5 is a top plan view of the lower 55 tray.

Figure 6 is a bottom plan view of the upper tray showing the manner in which the detachable handle is engaged with the lug.

Figure 7 is a detail showing the slotted 60 handle engaged with the lug.

Figure 8 is a plan view of the model taken of the fracture mandible.

Figure 9 is a sectional view taken approximately on the line 9—9 of Figure 8 for more 65 clearly disclosing the fracture; and

Figure 10 is a detail showing the parts of the model cemented together after the same has been sawed through and the line of fracture and the separate parts arranged to assume the normal position of the mandible. 70

In the drawings wherein for the purpose of illustration is shown the preferred embodiment of my invention, the numeral 1 designates generally the lower splint tray while the upper splint tray is denoted by the numeral 2. The lower tray is of substantially U-shaped formation provided with the inner and outer marginal flanges 3 and 4 respectively and the base portion 5 whereby a channel-shaped structure is provided. It will also be observed that the marginal flanges are disposed in diverging relation from the base plate 5. 80

Formed at each side of the lower splint tray 1 and more particularly in the free end portion of the outer marginal flange 4 are the spaced loops 6, the purpose of which will be presently described. Wire ligatures 7 are attached at one end to the respective loops 6. 85

A series of teeth 8 extend upwardly from the base plate 5 adjacent the free ends of the U-shaped tray in the manner as clearly suggested in Figures 4 and 5 of the drawings and the purpose of these teeth will also be 95 presently apparent.

The upper splint tray 2 includes a base portion 9 having an outer marginal flange 10. The central portion of the base plate 9 is pressed upwardly as indicated at 11 where- 100

by to form a substantially U-shaped channel in the tray between the arched portion 11 and the marginal flange 10 as suggested very clearly in the drawings.

5 A series of spaced loops 12 similar to the loops 6 are arranged in the marginal flange 10 adjacent the free ends of the substantially U-shaped channel and attached to these loops 12 are the wire ligatures 13 that cooperate 10 with the adjacent ligatures of the underlying loops 6 in the manner to be presently described.

Arranged on the bottom of the base plate 9 at the front portion thereof is the depending lug 14, the bottom face of which is flat 15 for engagement with the adjacent face of the base plate 5 of the complementary splint tray 1 when the trays are secured together. Suitable longitudinally extending slots 15 are 20 formed in the opposite side of the lug 14 adjacent the connection of the lug with the base plate 9 as indicated more clearly in Figure 3.

A pair of substantially channel-shaped shoes 16 are attached to the bottom face of 25 the base plate 9 directly beneath the free ends of the channel formed in the upper tray 2 and these channel-shaped shoes receive the rubber blocks 17. The channel-shaped shoes and the rubber blocks arranged therein are 30 positioned to cooperate with the upwardly projecting teeth 8 carried by the lower tray 1 in the manner to be presently described.

A handle such as is shown at 18 in Figures 35 6 and 7 of the drawings is adapted to be used in conjunction with the upper splint tray 2 and this handle is formed from a flat strip of metal. The inner end thereof is enlarged and is formed with a slot 19 in order that the fur- 40 cations may engage with the respective slots 15 formed in the lug 14 and the forward end of the lug will be disposed against the crown of the U-shaped slot 19 when the handle is in its innermost position so that the handle will be secured to the upper tray and the outer 45 end portion of the handle may be grasped to facilitate the insertion or removal of the upper tray.

The use of my improved fracture splint 50 may be briefly stated as follows. At the outset, an impression of the fractured mandible is taken with any ordinary lower impression tray. Then plaster of Paris is poured in the same and when the model has hardened, the same is removed from the tray and in Figure 55 8 of the drawings, I have illustrated the model thus formed.

The line $a-a$ indicates the line of fracture. The model 20 is then cut through the line of fracture with a fine hack saw after which the 60 sections of the cut model are assembled together to assume the normal position of the mandible and then the sections are cemented together in the manner as illustrated in Figure 10.

65 Subsequently a modelling compound im-

pression is taken on the corrected model shown in Figure 10 with the lower splint tray 1. A modelling compound impression of the upper jaw is also taken by the use of the upper splint tray 2. After impressions of 70 both jaws are properly made, the upper splint tray 2 is held in the mouth of the patient by the use of the detachable handle 18 that is engaged with the slotted lug 14.

The lower splint tray 1 is placed in the 75 mouth of the patient by the operator to substantially the proper position on the fractured mandible. The mouth of the patient is then closed to bring the splint trays into normal relation so that the lug 14 will engage 80 against the upper face of the base plate 5 of the lower splint tray 1 and at the same time, the teeth will bite into the respective rubber blocks 17. The adjacent pairs of wire ligatures 7 and 13 have their free ends twisted 85 together whereby to secure the splint trays together firmly. The teeth 8 will cooperate with the rubber blocks 17 to prevent lateral displacement of the splint trays with respect to each other while positioned in the mouth 90 of the patient. If necessary, appropriate jaw supports may be applied to the outside of the face to maintain the splint trays further against movement. The splint trays are maintained in the mouth of the patient until 95 the fractured bones have reunited. The patient may be fed by inserting food between the upper and lower splint trays that are spaced apart through the medium of the lug 14 as well as the channel-shaped shoes 17.

100 The simplicity of my device enables the parts to be readily and easily adjusted and with the use of a fracture splint of this character, the broken parts may be properly set so that when the broken bones have reunited, there will not be left any indication 105 that the mandible has been broken.

110 While I have shown the preferred embodiment of my invention, it is to be understood that minor changes in the size, shape and arrangement of parts may be resorted to without departing from the spirit of the invention or the scope of the appended claims.

What I claim is:

115 1. A fracture splint of the class described adapted to receive the upper and lower jaws comprising separable upper and lower complementary trays, means carried by one of the trays and adapted to contact the other tray for spacing the trays apart, and wire ligatures attached to the outer flanges of the trays for securing the same together, said spacing means being free of connection with 120 said other tray.

125 2. A fracture splint of the class described comprising separable upper and lower trays adapted to receive the upper and lower jaws, means including a depending lug carried by the front portion of the upper tray for solely contact engagement with the adjacent por-

tion of the lower tray to space said trays apart, and wire ligatures attached to the outer flanges of the trays for securing the same together.

- 5 3. A fracture splint of the class described comprising separable upper and lower trays adapted to receive the upper and lower jaws, means including a depending lug carried by the front portion of the upper tray for solely contact engagement with the adjacent portion of the lower tray to space said trays apart, and means carried by the trays for securing the same together, said last-mentioned means including a plurality of wire ligatures connecting the outer flanges of the trays.
- 10 4. A fracture splint of the class described comprising separable upper and lower trays adapted to receive the upper and lower jaws, means including depending lugs carried by the upper tray for solely contact engagement with the adjacent portion of the lower tray to space said trays apart, wire ligatures carried by the outer flanges of the trays for securing the same together, and means engaging said lugs for preventing lateral movement of the trays with respect to each other.

- 20 5. A fracture splint of the class described comprising separable upper and lower trays, each including a base plate having inner and outer marginal flanges, a depending lug carried by the base plate of the upper tray at the front portion thereof for solely contact engagement with the adjacent portion of the base plate of the lower tray to space said trays apart, said lug further providing a handle attaching portion, additional spacing means at the rear portion of the trays, and wire ligatures carried by the outer flanges of the separable trays for securing them together.

- 30 6. A fracture splint of the class described, comprising separable upper and lower trays, each including a base plate having inner and outer marginal flanges, a depending lug carried by the base plate of the upper tray at the front portion thereof for engagement with the adjacent portion of the base plate of the lower tray to space said trays apart, said lug further providing a handle attaching portion, additional spacing means at the rear portion of the trays, and means for securing the separable trays together, and means associated with the rear spacing means to prevent lateral movement of the trays with respect to each other.

- 40 7. A fracture splint of the class described comprising separable upper and lower trays adapted to receive the upper and lower jaws, a depending lug carried by the front portion of the upper tray for engagement with the adjacent portion of the lower tray to space said trays apart, and means carried by the trays for securing the same together, and ad-

ditional means for preventing lateral movement of the trays with respect to each other, said last-mentioned means including rubber blocks carried by the base portion of one of the trays, and projecting teeth carried by the adjacent portion of the base of the other tray and adapted to bite into the respective rubber blocks.

In testimony whereof I affix my signature.
